[57] CLAIM

The ornamental design for a pan insert, substantially as shown.

DESCRIPTION

FIG. 1 is a top perspective view of a pan insert showing my new design;

FIG. 2 is a top plan view thereof;

FIG. 3 is a front elevational view taken in the direction of the arrows along line 3—3 of FIG. 2;

FIG. 4 is a rear elevational view as seen from the right of FIG. 2;

FIG. 5 is another front elevational view taken in the direction of the arrows along line 5—5 of FIG. 2; and
FIG. 6 is another rear elevational view as seen from the top of FIG. 2.
